US0D1077470S

(12) **United States Design Patent** (10) **Patent No.:** **US D1,077,470 S**
(45) **Date of Patent:** **** Jun. 3, 2025**

(54) **CASE**

- (71) Applicant: **Apple Inc.**, Cupertino, CA (US)
- (72) Inventors: **Christina J. Smiechowski**, West Hollywood, CA (US); **Duy P. Le**, Los Angeles, CA (US); **Jeffrey Scott Croyle**, San Francisco, CA (US); **Matthew Phillip Casebolt**, Fremont, CA (US); **Matthew Vincent Costello**, Soquel, CA (US); **Elvin Chu**, San Francisco, CA (US); **Guillaume Raoult**, San Francisco, CA (US); **Zu-Ning Chen**, San Francisco, CA (US); **Christopher Kuh**, San Francisco, CA (US); **Robert Brunner**, Glen Ellen, CA (US)
- (73) Assignee: **Apple Inc.**, Cupertino, CA (US)
- (**) Term: **15 Years**
- (21) Appl. No.: **29/913,462**
- (22) Filed: **Oct. 2, 2023**

Related U.S. Application Data

- (63) Continuation of application No. 29/784,499, filed on May 19, 2021, now Pat. No. Des. 1,000,117.
- (51) **LOC (15) Cl.** **03-01**
- (52) **U.S. Cl.**
USPC **D3/294**; D13/108

(57)

CLAIM

The ornamental design for a case as shown and described.

DESCRIPTION

FIG. 1 is a top front perspective view of a case showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the case that form no part of the claimed design.

1 Claim, 8 Drawing Sheets
